CONTAINER

Jerome J. Dorfman, 601 39th St., Brooklyn, N.Y.
Filed Apr. 17, 1961, Ser. No. 103,478
3 Claims. (Cl. 229—14)

This invention relates to a container, and more particularly concerns a container having a flexible inner bag disposed within and supported by a relatively rigid outer carton.

It has been proposed to package and store fluid, semifluid and freely flowing materials in thin walled, flexible bags, which in turn are disposed within cartons formed of cardboard, corrugated board or the like. Such bags are usually formed of thin plastic films and include a combination filling and dispensing spout in relatively narrow, elongated form. Since the bag is not positively anchored to its carton, there may be a tendency for the bag to shift within the carton as the same is transported and handled. Accordingly, the spout portion of the bag may shift relative to its initial position within the carton.

Such shift in position of the spout necessitates the complete opening of the closure flaps of the carton in order to make the spout accessible for dispensing the contents of the bag. Also, the movement of the bag relative to the carton may be such as to leave the spout in an inaccessible position even after the carton flaps are completely opened.

Accordingly, one object of this invention is to provide a container of the character described, which includes improved means for anchoring the spout portion of the bag to its initial position and thereby rendering such spout portion readily accessible for dispensing the contents of the bag.

Another object of this invention is to provide a container of the character described, wherein access to the spout of the bag may be gained without completely opening the closure flaps of the carton.

A further object of this invention is to provide a combination carton and flexible bag having a spout portion; the closure flaps of the carton being modified to provide means for anchoring the spout portion of the bag and to make the same readily accessible and movable to a dispensing position.

Still another object of this invention is to provide a carton and associated flexible bag having a filling and dispensing spout, wherein the inner closure flap of the carton includes means for anchoring the bag spout and the outer closure flap of the carton includes means for gaining access to the spout anchoring means while leaving the inner and outer closure flaps in their closed position.

Other objects of this invention will in part be obvious and in part hereinafter pointed out.

In the drawing,

FIG. 1 is a front elevational view of the bag portion of the container embodying the invention;

FIG. 2 is a perspective view of the carton portion thereof, with the closure flaps in their open positions;

FIG. 3 is a top plan view of the carton with the inner closure flaps in their closed position;

FIG. 4 is a view similar to that of FIG. 3, and showing both the inner and outer closure flaps in their closed position;

FIG. 5 is a sectional view taken on the line 5—5 of FIG. 3.

Essentially, the container of the instant invention, generally designated at 10, comprises a flexible bag 11, as shown in FIG. 1, which is formed of thin plastic film, Cellophane or the like and seamed along the edges thereof, all in a manner known in the art. Bag 11 includes a somewhat narrow, elongated spout portion 12 by which the bag is filled with fluids, semifluids or freely flowing material; the spout portion 12 then being sealed as at 12A

2

by a transverse seam. As bag 11 is usually formed of a thermoplastic sheeting or thermoplastic coated sheeting, such seams and seals may be formed by hot seaming and sealing tools known in the art.

Bag 11 is disposed within and supported by a carton 13, such as shown in FIG. 2; such carton being formed of substantially rigid materials such as cardboard, corrugated board or the like. Carton 13 comprises a bottom wall portion 13A; side walls 14, 15, end walls 16, 17; a pair of inner closure flaps 18, 19 hinged along edges 18A, 19A respectively to the top edges of side walls 14, 15 respectively; and a pair of outer closure flaps 20, 21 hinged along edges 20A, 21A respectively to the top edges of end walls 16, 17 respectively.

Inner closure flaps 18, 19 have outer edges 22, 23 respectively, which edges are in substantially abutting relation when flaps 18, 19 are in their closed position. Flaps 18, 19 also have side edges 24, 25. Similarly, outer closure flaps 20, 21 have outer edges 26, 27 respectively, adapted to abut in the closed position of said flaps, and side edges 28, 29.

Usually, with the closure flaps 18, 19; 20, 21 of carton 13 in their open position; bag 11 is disposed within the carton and filled by way of spout portion 12, by known filling means. Preferably, bag 11 is so positioned within carton 13 as to locate spout portion 12 in a corner of the carton, as adjacent the intersection of carton walls 15, 16. After filling bag 11, spout portion 12 is transversely sealed at 12A.

Means is provided for anchoring spout portion 12 in its initial position, to avoid undue displacement thereof during transportation and handling operations. To this end, inner flap 19 is formed to provide a section 30 which may be displaced relative to the flap proper. Section 30 is of rectangular shape and is refined by perforation lines 31, 32 extending from edges 19A and 25 respectively. Section 30 may thus be pressed out of the plane of flap 19 but will remain hinged to wall 15 along hinge line 19B.

Flap section 30 is formed with a pair of parallel slits 33, 34 extending from edge 25 towards but short of perforation line 31. The upstanding spout portion 12 is adapted to be threaded through slits 33, 34 of flap section 30 to secure the same in place, as shown in FIG. 5, the terminal end of the spout portion being disposed beneath the flap. Thus, the spout portion 12 is frictionally gripped in flap section 30 and supplemental seals are provided for the spout portion along slits 33, 34.

After the inner flaps 18, 19 are turned inwardly and downwardly to their closed position, the outer flaps 20, 21 are moved to their closed position, bringing the same in superposed relation to the inner flaps 18, 19 and are secured thereto by glue, staples, or the like, in a manner known in the art.

Outer closure flap 20 is formed to provide a rectangular shaped, displaceable access section 36 which is defined by perforation lines 37, 38 extending from edges 28, 20A respectively. Section 36 is hinged to carton wall 16 along edge 20B. When the closure flaps of carton 13 are in their closed position, access section 36 overlies anchor section 30.

To gain access to the spout portion 12 without opening the closure flaps 18, 19; and 20, 21; access section 36 of outer flap 20 is displaced from the flap by pressing or pulling the same, which action is facilitated by a finger opening 39 formed in the line 37 of perforations. Thus, access section 36 may be displaced outwardly of flap 20 along hinge line 20B to expose anchor section 30, which in turn is also displaced from its flap 19; displacement being facilitated by a finger opening 35 formed in perforation line 32.

With anchor section 36 raised along hinge line 19B,

the spout portion 12 may be disengaged from the section 36 and raised to an upright dispensing position. The upper end of spout portion 12 is then cut transversely to allow the contents of bag 11 to be dispensed therefrom.

It will be apparent that the spout portion 12 is kept in its initial position relative to the closure flaps and will not be displaced therefrom, notwithstanding any movement of the bag 11 proper relative to carton 13. Furthermore, it is not necessary, to completely open the closure flaps in order to gain access to said spout portion, since the sections 36 and 30 are quickly and easily displaced from their respective closure flaps to make spout portion 12 quickly accessible.

As various changes might be made in the embodiment of the invention herein shown without departing from the spirit thereof, it is understood that all matter described or shown herein shall be deemed illustrative and not limiting except as set forth in the appended claims.

Having thus disclosed my invention, I claim as new and desire to protect by Letters Patent:

1. A container comprising a one piece carton having opposed side walls and opposed end walls with closure flaps respectively extending from one end of said side and end walls and hingedly connected thereto, a bag disposed within said carton, said bag including a narrow, elongated, flexible and flattenable spout portion for filling and dispensing the contents of the bag, said bag being disposed within said carton to locate the spout portion at said one end thereof and adjacent a corner portion thereof, the closure flaps extending from one set of carton walls being foldable toward each other and the closure flaps extending from the other set of carton walls being foldable toward each other and in their folded position overlying the first mentioned closure flaps in their folded position, whereby one of the outermost folded flaps includes an end portion in overlapping relation to an end portion of one of the innermost folded flaps, each of said flap end portions including a flap section displaceable from the plane of the flap end portion with which it is associated, each of said flap sections being hingedly connected to a carton wall at

5 said one end thereof, said flap sections overlying each other when said closure flaps are in their folded, closed position, the innermost of said flap sections being formed with spaced slits to frictionally receive said bag spout in

10 the flattened condition thereof to seal said spout and to retain the same in a determined position relative to said carton side and end walls, the outermost flap section being hingedly displaceable while the closure flap with which it is associated is in its folded, closed position, to expose the underlying inner flap section, whereby said inner flap section may be hingedly displaced while the closure flap with which it is associated is in its folded, closed position, to raise the spout portion engaged therewith and to allow the spout portion to be disengaged therefrom for operative use.

15 2. A container as in claim 1 wherein each of said flap sections is defined by intersecting perforation lines extending respectively from the hinged connection thereof to the associated carton wall, and the end edge of the flap end portion, with which the flap section is associated.

20 3. A container as in claim 1 and further including finger opening means in said flap sections for manually displacing the respective flap sections from their associated flap portions.
